GRABHOOK

Albert L. Stahl, Cupertino, Calif.

Application March 28, 1944, Serial No. 528,378

6 Claims. (Cl. 294—106)

This invention relates in general to an improved grab hook of the type adapted to be suspended from a crane for engagement with an object to be lifted, and in particular the invention is directed to improvements in a grab hook of the type adapted to grip and lift sheet metal or plates; the device being especially useful in ship-building yards where cranes are employed to move the steel plates from place to place.

The principal object of this invention is to provide a grab hook adapted to be suspended from a crane, and arranged for control solely by the crane operator; i. e., the crane operator at his station remote from the grab hook can place the latter on an upstanding plate and effect gripping engagement of said grab hook therewith, and after the plate has been moved by the crane the operator can release and remove the grab hook therefrom. In other words, the grab hook is controlled solely by proper manipulation of the crane and without the necessity of an attendant at the grab hook.

An additional object of the invention is to provide a grab hook for metal plates which comprises, in combination with a body and plate engaging jaws pivoted thereon, unique means including a one-piece supporting eye and hook arranged so that the operation of the jaws is controlled by manipulation of said one-piece eye and hook relative to a cross pin on the body, and which pin the hook is adapted to releasably engage.

Other objects of the invention are to provide a grab hook which can be readily and quickly applied to or released from a steel plate, and which is capable of handling plates of different thickness without necessity of any adjustment.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a side elevation of the grab hook as suspended from a crane; the grab hook being shown in full lines in its initial or inoperative position, while the one-piece supporting eye and control hook of the device is shown in dotted lines in the position it occupies after release from the cross pin but before raising to effect gripping of the plate.

Figure 2 is a side elevation of the grab hook

engaged in gripping relation with a plate for lifting the latter.

Figure 3 is an end view of the device.

Figure 4 is a fragmentary elevation, on reduced scale, showing a modified form of the control hook.

Referring now more particularly to the characters of reference on the drawings, my improved grab hook comprises a body made up of a pair of upstanding plates 1 disposed in spaced parallel relation, said plates being symmetrical and decreasing in width from top to bottom. A vertical throat 2 is cut in the plates upwardly from the lower end thereof; such throat being relatively deep and at its lower end flaring outwardly on both sides, as at 3. A pair of flat arms 4 are pivoted at their lower ends between the plates 1 adjacent the lower end of the latter but on opposite sides of the throat 2; the arm pivots being shown at 5 and these pivots serving to maintain the plates 1 against separation.

The arms 4 project upwardly and outwardly from pivots 5, and terminate at their upper and outer ends clear of the plates 1. The arms 4 above pivots 5 and at their inner edges are laterally enlarged and formed as eccentric toothed jaws 6; said jaws being adapted to swing into the throat 2 upon upward and inward swinging movement of the arm 4.

A pair of parallel spaced links 7 straddle each of the arms 4 at its upper end and are secured thereto by pivots 8.

An eye 9 cut from a flat sheet of metal of lesser thickness than the space between plates 1 is disposed above the latter in a plane parallel to but between the plane of said plates. The pairs of links 7 extend upwardly in converging relation and at their upper ends straddle the eye 9 on opposite sides adjacent but short of the lower end thereof; pivots 10 securing the links 7 to said eye.

Below the pivots 10 the eye 9 is formed with a hook 11 which is open to one edge of the eye at right angles to a cross pin 12 fixed between the plates 1 at the top centrally between the sides of said plates. The hook 11 is adapted to engage cross pin 12 from below with the eye 9 extending vertically thereabove, as shown in full lines in Fig. 1. This is the initial or inoperative position of the grab hook wherein the jaws 6 are held clear of the throat 2.

In use the above described grab hook is suspended from the traveling block 13 of the crane by means of the lifting hook 14 on such block, and which hook is engaged through the vertical eye 9 of the grab hook.

With the grab hook in the position shown in Fig. 1, the crane operator manipulates the crane and lowers the grab hook so that the upstanding plate P to be lifted enters throat 2; the flaring portions 3 of said throat guiding the plate into the latter. Thereupon, and as soon as plates 1 are supported by plate P, the operator lowers the eye 9 until the hook 11 drops from cross pin 12, moves the eye 9 laterally to the position shown in dotted lines in Fig. 1 by manipulation of the crane, and thereafter lifts eye 9 with hook 11 clear of cross pin 12. Continued lifting movement of eye 9 causes the links 7 to swing the arms 4 upwardly and inwardly, whereupon the eccentric jaws 6 come into gripping engagement with the plate 9. As so gripped the plate is lifted by the crane and moved to the desired place.

To release the grab hook from the plate after the latter has been seated on the ground, the operator lowers eye 9 to release the jaws 6 from the plate, and then manipulates said eye by the crane to re-engage hook 11 with cross pin 12, whereupon the grab hook may be lifted free of the plate as the jaws are then held in inoperative position clear of the throat.

The above described operation can be readily and speedily accomplished by the crane operator and it is not necessary for another person to attend the placement or removal of the grab hook from the work. One of the essential features of my improved grab hook is the one-piece rigid supporting eye 9 and hook 11 which permits the operator to accomplish the operation in the manner described.

In the modification shown in Fig. 4 the eye 9a includes a hook 11a which is double; i. e. the hook includes pin receiving notches N open to opposite edges of the eye, whereby to facilitate engagement of the hook with the pin. With the above double hook, the crane operator can readily engage the hook with the pin, regardless of the side of the pin to which the hook is disposed when the device is in a released position.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In a grab hook which includes an upstanding member adapted to seat on an object to be lifted, jaws mounted on the member in position for movement to engage said object therebetween, an upstanding connection element disposed above the member, and means between the jaws and element, including a pair of upwardly extending links pivotally connected at their upper ends to said element, arranged to

close said jaws on the object upon upward movement of the element relative to said member; a hook rigid with and depending from said element, and a pin projecting from the member above said jaws, the element being swingably movable in a vertical and horizontal direction in a plane intersecting said pin, and the hook being disposed to releasably engage said pin on its underside.

2. In a grab hook which includes an upstanding member adapted to seat on an object to be lifted, jaws mounted on the member in position for movement to engage said object therebetween, an upstanding connection element disposed above the member, and means between the jaws and element, including a pair of upwardly extending links pivotally connected at their upper ends to said element, arranged to close said jaws on the object upon upward movement of the element relative to said member; a hook formed integral with said element, and a pin projecting from the member above the jaws, the element being swingably movable in a vertical and horizontal direction in a plane intersecting said pin, and the hook being open to one side of said element and adapted to releasably engage said pin on its underside.

3. A grab hook as in claim 2 in which the element is an eye adapted to receive the lifting hook of a crane; the hook being formed at the lower end of said eye.

4. In a grab hook, an upstanding body comprising spaced flat plates secured in facing parallel relation, said body having a vertical throat cut therein from and open to its lower end, eccentric jaws pivoted between the plates in position to grip an object in the throat, jaw actuating arms rigid with said jaws extending upwardly in diverging relation from between said plates to points clear of the body, pairs of parallel links, the links of each pair straddling and pivoted at one end in connection with the outer end of one of the arms, said pairs of links extending upwardly from the arms in converging relation above the body, an eye disposed above the body, said eye being flat and parallel to the body, the upper ends of said pairs of links straddling and being pivoted to the eye on opposite sides thereof, an integral hook formed with said eye adjacent its lower end, said hook opening to one side edge of the eye, and a rigid cross pin connected between the body plates at the top in vertical alinement with said throat, the hook being adapted to releasably engage said pin on its underside.

5. A grab hook as in claim 4 in which the thickness of the flat eye hook is less than the space between the body plates whereby the hook projects therebetween for engagement with said cross pin.

6. A grab hook as in claim 1 in which the hook is double and includes pin receiving notches open to opposite sides thereof.

ALBERT L. STAHL.
